UNITED STATES PATENT OFFICE.

ALBERT E. SCHERER, OF GLENVILLE, OHIO.

EAVES-TROUGH HANGER.

No. 816,941.

Specification of Letters Patent.

Patented April 3, 1906.

Application filed July 13, 1904. Serial No. 218,451.

To all whom it may concern:

Be it known that I, ALBERT E. SCHERER, a citizen of the United States, residing at Glenville, Cuyahoga county, Ohio, have invented 5 certain new and useful improvements in Eaves-Trough Hangers, of which the following is a specification that will enable those skilled in the art to which my invention pertains to make and use the same, reference being had to the accompanying drawings, forming a part thereof.

My invention pertains to eaves-trough hangers made of strips punched or cut from sheet metal. Its objects are to simplify the 15 construction of such hangers, to reduce the number of parts therein, thereby effecting a saving of metal in the construction and facilitating the operation of assembling and uniting the parts, and to so shape these parts that 20 in cutting them from sheets there is practically no waste or scrap produced and so that two parts of a like kind may be produced at one punching cut where but one was produced before, and in other features, as will be 25 hereinafter set forth.

The invention consists of a two-part eaves-trough hanger having features of construction which will be described in detail farther on.

30 The accompanying drawings show my invention in its details and general forms now deemed most desirable by me; but changes not requiring the exercise of invention and within the skill of a good mechanic might be 35 made therein without departure from the spirit of my invention as set forth in the claim at the end of this specification.

Figure 1 is a view of a combined cross-bar and binder-strap blank, which forms one 40 member of my hanger, and a sheet of metal with holes punched therein and lines indicating the punching cuts for cutting the blanks therefrom. Fig. 2 is a side elevation of one member of the cross-bar and tie after the blank has been pressed into final shape for 45 use in the hanger. Fig. 3 is a bottom plan view of the same. Fig. 4 is a perspective view of the other member of the hanger which forms the roof-strap. Fig. 5 is a side 50 elevation of the cross-bar and roof-strap united by a single rivet, showing also the application of the hanger to an eaves-trough, the full lines showing the members of the hanger in their relative positions or commercial form as they leave the factory, while the dotted lines show the positions to which they

are bent by hand when being applied to an eaves-trough and the roof of a building. Fig. 6 is a perspective view of the hanger alone, showing a portion of the roof-strap broken away.

My hanger is comprised of two main members, A being the combined cross-bar and binder-strap and B the roof-strap, the two being united by a single rivet C, as shown in 65 Figs. 5 and 6.

The shape and method of cutting the cross-bar and binder are clearly shown by Fig. 1, in which the blank A, detached from the sheet, is shown as having a wide end a and a 70 narrower opposite end portion a² of the same length as the wider portion, these two portions being joined by a tapering mid-portion a'. In practice I prefer to make each of the three portions about one-third of the total 75 length of the piece; but in any event the end portions must be of the same length regardless of the proportionate length of the tapering mid-portion. Rivet-holes a³ and strap-holes a⁴ are punched in the sheet previously 80 to the punching cuts that sever the members from the sheet. These severing cuts d and d' are made by a punch and its companion die, shaped like the section crossed by diagonal shade-lines, which punches or cuts its blank 85 from the body of the sheet at a sufficient distance back from its edge to leave or form another blank between the one it is actually cutting out of the body of the sheet and the edge of the sheet. Owing to the shape of the 90 blanks and this method of cutting them, I am enabled to cut two blanks at each operation of the cutting-punch and, as will be noted, to cut them without leaving any waste material.

The blanks thus punched and cut are then 95 operated upon by a stamping-machine which forms them as shown in Figs. 3 to 6, inclusive—that is, with a raised hook or groove a⁵ at one end, in the crown of which is the strap-hole a⁶, an arched cross-bar portion a⁷, in 100 which is the rivet-hole a⁸, and a semicurved portion a⁹ at the inner end of the cross-bar portion. These features of the member are formed in the wider portion a' of the blank, and the tapering portion a' extends from the 105 semicurve and merges into the narrower extension a², as shown.

The portion a' of the blank has sufficient width of material to form the stiff rigid cross-bar. The tapering mid-portion a' has sufficient material at its wide end to firmly support the outer or free edge of the eaves-

trough, while the portion a^2 is narrow enough to be sufficiently flexible to permit of its being manipulated and bent by hand without the necessary employment of special tools of any kind.

5 The other member of the hanger, the roof-strap B, is a plain rectangular piece with a rivet-hole b punched in one end and two nail-holes b' punched in the other end.

10 The parts are assembled and joined by a rivet c , as shown by full lines in Fig. 5, and the hangers are complete and marketable in this form and are so shipped to consumers. The method of applying them to eaves-troughs and the forms to which they are bent by hand is shown by dotted lines in Fig. 5 and by the perspective, Fig. 6. The raised hook a^5 is placed astraddle of the inner edge d of the trough D. The arched cross-bar a^6 spans the trough, and the semicurve rests upon the bead d' at the outer edge of the trough. The remaining tapering and straight portions at a^2 of the member are then bent by hand beneath and around the trough, the free end being slipped through the strap-hole a^4 and bent down, as shown in said figures. The inward kink or bend a^8 to fit the strap fairly under the trough-bead may be formed previously by a reverse curve, or it may be 20 struck in by pressure or by a hammer-blow at the time of application. The other member, the roof-strap B, is bent back upon itself to any angle or angles to adapt it, as shown, to the height from and slope of the roof, upon 25 which it is secured by nails driven through the holes b' .

30 By my invention I am enabled to effect a

considerable saving in the metal actually used in the construction and more by the avoidance of scrap. There is also a saving of time effected 40 by the avoidance of several operations in the formation of the parts heretofore deemed necessary and a saving of time in the assembling and uniting of the parts. These various savings in matters of material and time 45 combined so materially reduce the cost of sheet strap-hangers that I am enabled to make and sell them in competition with wire hangers, which while not considered as good as the strap-hangers have been produced so 50 much more cheaply than the strap-hangers that they have held the market against them.

Having thus described my invention, what I claim as new and useful, and desire to secure by Letters Patent, is—

55 An eaves-trough cross-bar and loop-hanger made of a single piece and comprising a wide portion at one end for the rigid cross-bar, a narrower portion at the other end to provide a flexible part for interlocking with the cross-bar 60 and a tapering mid-portion of a length to afford sufficient support to the free edge of the eaves-trough, said end portions being of the same length so that successive pieces, inverted end for end, may be struck from a sheet at 65 a single operation without waste.

In testimony whereof I have signed my name to this specification in the presence of two subscribing witnesses.

ALBERT E. SCHERER.
